CONCRETE BLOCK MACHINE

Newell B. Hanson, Lake Lillian, Minn.

Application October 10, 1945, Serial No. 621,507

3 Claims. (Cl. 25—41)

1

My present invention relates to improvements in machines for producing concrete building blocks and the like. While the machine, herein illustrated, is designed particularly for use in the manufacture of flat imperforate blocks of the tongue and groove variety such as are widely used in the construction of silos, it will be understood that the invention hereof is equally adaptable to machines designed for building various different shapes and kinds of building blocks and the like.

In the manufacture of concrete products of the variety mentioned, it is important to compress the work batch of concrete or analogous cementitious material within the mold cavity of the machine to a maximum possible density, whereby to obtain the maximum possible strength in the finished product. In the building block art, this has usually been accomplished by reciprocating tampers, and in machines of the prior art it has been customary to pack the material into the mold by a laterally spaced series of tampers working in unison and engaging the upper surfaces of the work batch in synchronization. This prior art practice of packing the work batch into the mold cavity by synchronized tampers, having pretty much the same effect as a single, but larger and heavier, tamper, has been found objectionable for the following reasons, to wit:

a. The relatively great amount of power required to reciprocate the several tampers in unison;

b. The terrific jar or vibration set up by the simultaneous impact of the several tampers; and

c. The relative density of the material was often much less than could be desired.

In accordance with the present invention, the above objections are overcome and the density of the final product is improved by operating a laterally spaced series of reciprocating tampers in out-of-phase relationship one with the other, whereby different tampers come into engagement with the surface of the work batch at different times, thereby causing the material of the work batch to shift and flow within the mold cavity during the tamping operation, and which shifting and flowing action results in greatly improved density in the finished product. Also, this reciprocation of the tampers in out-of-phase relationship to one another consumes considerably less power by dividing up the load and distributing it more evenly throughout the entire period of operation, and this, in turn, greatly reduces the vibration of the machine, thereby making for long machine life and better working conditions in the vicinity of the machine.

Another important object of the present invention is the provision of an improved means for filling the rectangular frame which serves to transfer a work batch of material to the mold

cavity. In accordance with the invention, the said transfer device or frame is filled with concrete or equivalent cementitious material in a fluid state from a hopper or other source of supply through a conduit terminating directly above said transfer device when the same is moved to its receiving position in offset relation to the mold, and means is provided for automatically closing the extreme delivery end of this delivery conduit upon movement of the transfer frame or device from its receiving to its delivery position above the mold cavity.

Still another highly important object of the invention is the provision of highly efficient mechanism for automatically conveying the pallet, which forms the bottom of the mold cavity, into operative position and conveying the said pallet and molded product from the mold cavity to a suitable discharge point. This important phase of the invention comprises horizontal and vertical conveyor elements and a highly efficient automatic stop device for stopping horizontal movements of the pallet at a position directly below the mold cavity and from which the pallet is moved vertically into engagement with the mold, and which stop device is automatically retracted so as to permit continuation of the horizontal movement upon lowering of the pallet to the horizontal portion of the conveyor upon completion of the molding cycle.

A still further and highly important object of the invention is the provision of an improved automatic control mechanism for the above mentioned conveyor mechanism.

The above and other highly important objects and advantages of the invention will be made apparent from the following specification, claims, and appended drawings.

In the accompanying drawings, which illustrate a preferred embodiment of the invention, like characters indicate like parts throughout the several views:

Referring to the drawings:

Fig. 1 is a front perspective view of a machine incorporating a preferred embodiment of the invention;

Fig. 2 is a view of the machine of Fig. 1 in side elevation, showing the side thereof opposite the side shown in Fig. 1;

Fig. 3 is a view in side elevation showing the opposite side of the machine from that shown in Fig. 2;

Fig. 4 is an enlarged rear elevation of the machine;

Fig. 5 is a sectional view taken approximately on the line 5—5 of Fig. 4;

Fig. 6 is a fragmentary view corresponding to Fig. 5 but showing somewhat different position 60 of the parts;

Fig. 7 is a detail sectional view taken on the line 7—7 of Fig. 5;

Fig. 8 is a fragmentary view in front elevation of the upper portion of the machine, with some parts removed and some parts shown in section;

Fig. 9 is a fragmentary horizontal sectional view taken on the line 9—9 of Fig. 7;

Fig. 10 is a detail sectional view taken on the line 10—10 of Fig. 5;

Fig. 11 is a detail sectional view taken on the line 11—11 of Fig. 4; and

Fig. 12 is an enlarged fragmentary sectional view taken on the line 12—12 of Fig. 6, with some parts omitted.

The frame of the machine, illustrated, is of generally rectangular shape having suitable cross members and vertical and horizontal extensions hereinafter described. This frame structure is indicated as an entirety by 1. The mold, indicated as an entirety by 2, is supported by and rests on longitudinal side rails 3 of the frame 1. This mold 2 provides a rectangular molding cavity 4 that is open at top and bottom. The said mold 2 comprises two identical L-shaped wall-forming sections each comprising a longitudinally extended side wall-forming section 5 and an end wall-forming section 6 rigidly anchored thereto by nut-equipped bolts or the like 7. The side rail or wall 5 or each L-shaped mold wall-forming section is extended to overlap and rest upon opposite frame rails 3 (see particularly Fig. 9). The left-hand extended ends of the opposite L-shaped mold sections, with respect to Fig. 9, are bifurcated to receive opposite ends of an intermediately pivoted lever 8. The lever 8 is pivoted at 9 to an adjacent side frame rail 3 and the ends thereof are connected to opposite of said mold frame sections by slot and pin connections, as at 10. The right-hand extended ends, with respect to Fig. 9, of the opposite L-shaped mold sections are bifurcated to receive opposite end portions of an intermediately pivoted lever 11. This lever 11 is intermediately pivoted to an underlying frame rail 3 at 12 and has two of its opposite free end portions connected to the bifurcated end portions of the opposite mold frame sections by slot and pin connections as at 13 (see Fig. 9). The intermediately pivoted lever 11 is provided with a crank arm 14 which is connected to a pitman arm 15 at 16, and which, pitman arm, and its driving connections will later be described. It should here be noted that the opposite L-shaped mold sections are normally held against lateral separation by rollers 17 that are suitably journalled at their lower ends in the frame rails 3 and at their upper ends in overlying frame rails 18 that are coextensive with and extend parallel to the frame rails 3. By reference particularly to Fig. 9, it will also be seen that the mold frame extensions are formed to provide cam surfaces 19 for reception of the rollers 17 to permit relative opening movements of the opposite L-shaped mold sections one in respect to the other. This mold and the operating connections thus far described are old in the art, but it will be noted that the intermediately pivoted levers 8 and 11 are parallel and are so angularly disposed with respect to the mold frame extensions to which they are connected that counterclockwise movements of said levers 8 and 11, with respect to Fig. 9, shift the opposite L-shaped mold sections longitudinally one with respect to the other and also tend to force the same apart in a direction forwardly and rearwardly of the machine. Hence, it will be seen that when the levers 8 and 11 are

moved in counterclockwise directions with respect to Fig. 9, the opposite L-shaped mold sections will open, and when said levers 8 and 11 are moved in clockwise directions with respect to Fig. 9, the mold sections will be brought together or back to the position shown in Fig. 9.

Now, by reference particularly to Figs. 5, 6, and 9, it will be seen that a shelf 20 is secured to and extends from one of the side wall-forming sections 5 of the mold. This shelf 20 forms an extension of the upper surface of the attached mold wall member and at its projected end is supported by suitable angle iron supporting elements 21 or the like from the longitudinal frame rails 3. The supporting members 21 are fast on the shelf 20 and slidably engage the upper surfaces of rails 3.

Mounted for sliding movements longitudinally of the machine and above the mold 2 and its shelf-acting flange 20 is a transfer device (often referred to in the trade as a troweler) 22. This transfer device 22 is in the nature of a rectangular box-like frame that is open at its bottom and top and is slidably supported from the forwardly and rearwardly extending frame rails 18 as shown best in Fig. 7. By reference to Fig. 7, it will be seen that the end walls of the transfer device or troweler 22 are provided with vertically-spaced forwardly and rearwardly extending flanges 23 forming a guideway therebetween for reception of guide flanges 24 carried by opposite frame rails 18.

The bottom edges of the transfer device or troweler 22 run in close working clearance with the upper surface of plate 20 and mold 2, and the upper surfaces of said transfer device or troweler 22 work slidably under the discharge end of a material delivery conduit 25 which may be assumed to depend from a suitable source of supply, such as a hopper 26. The transfer device 22 is adapted to slide from the receiving position thereof shown in Fig. 6 to the delivery position shown in Fig. 5, in which latter position the said transfer device is directly above the mold cavity. It should here be noted that the rear wall of the transfer device or troweler 22 carries a valving plate 27 that has its upper surface disposed in the plane of the upper edge of the transfer device 22 and serves to close off the discharge end of the delivery conduit 25 when the transfer device 22 is moved out from under said conduit to its delivery position above the mold. The transfer device 22 is adapted to be moved from its receiving position of Fig. 6 to its delivery position of Fig. 5 by means of a pair of pitman arms 28 shown best in Figs. 2, 3, 4, and 1.

A tamping plate 29 is loosely pivoted on the front longitudinal wall of the transfer device 22 by transversely projected trunnions thereon 60 that seat in upwardly opening bearing brackets 30. The upwardly opening bearing brackets 30 are carried by forwardly projecting flanges of the transfer device 22. In its upwardly extended inoperative position shown in Fig. 5, the tamping plate 29 rests against a flange 31 on the upper front edge of the transfer device or troweler 22. The bottom of the tamping plate 29 is, in the preferred form illustrated, corrugated on its bottom surface, which bottom surface is adapted to contact and form similar corrugations in the upper surface of the material in the mold cavity when said plate 29 is in its lower operative position shown in Fig. 6.

During the molding operation, the mold cavity 70 is closed at its bottom by a pallet 32 that is made

up of upper and lower plates and intervening spacers. In this machine, as in other machines of this general character, the pallet 32 is removed from its operative position after the molding operation with the molded product resting thereon and usually supports the molded product until dry and set.

The pallet 32 is supported in its operative position shown in Fig. 7 and is elevated to and retracted from operative position by an elevator mechanism comprising a laterally spaced, forwardly and rearwardly extending pair of I-beams 33. The upper surfaces of the I-beams 33 are provided with permanently secured plates 33' for direct engagement with the pallet. The front ends of the I-beams 33 of the elevator mechanism are provided with guide shoes 34 that are slidably mounted in vertically extended guide channels 35 of channel-shaped guide bars 35' mounted fast on the inner surface of a front frame cross member 36. The guide channels 35' are provided with stops 37 for limiting downward engagement of the shoe-equipped ends of the I-beams 33. The rear ends of the elevator I-beams 33 are interconnected by an inverted L-shaped cross member 38, the opposite ends of which are extended laterally outwardly beyond the opposite beam 33 and are slidable in guide channels formed in the rear upright L-shaped corner posts 39 of the frame 1. The elevator I-beams 33 are thus guided for true vertical movements. The elevator I-beams 33 are supported and moved upwardly and downwardly by forwardly and rearwardly located pairs of toggle arms, indicated by 40 and 41 respectively. The upper ends of the pair of toggle arms 40 are pivotally connected to the opposite I-beams 33 at 42, and the upper ends of the pair of toggle arms 41 are pivotally connected to the interconnecting cross member 38 between the elevator beams 33 at 43. The lower ends of the toggle arms 40 are pivotally connected to the frame 1 at 44, and the lower ends of toggle arms 41 are pivotally connected to the frame 1 at 45. The toggle arms 40 and 41 are operated by a rock shaft 46 through the medium of oppositely extended crank arms 47 fast on the rock shaft 46 and rigid links 48 and 49 respectively. The rock shaft 46 is journalled in frame-supported bearings 46a. By reference particularly to Fig. 2, it will be seen that the rock shaft 46 is driven by connections comprising a crank arm 50 and a pitman 51 from other driving connections hereinafter described.

The conveyor mechanism for the pallet 32 comprises, in addition to the elevator mechanism above described, means for moving the pallet laterally to and from the elevator beams 33 when said beams are in their retracted lower positions. This lateral conveying means comprises a plurality of laterally spaced rollers 52 journalled in bearings 53 in the front frame cross member 36 and in similar bearings carried by a frame cross member 54 at the rear of the machine. The rear bearings for the rollers 52 are indicated by 55, see particularly Fig. 6. The plane of the upper surfaces of the several conveyor rollers 52 is just slightly above the plane of the upper surfaces of the plates 33' of the elevator beams 33 when said beams are lowered to their extreme inoperative positions shown by dotted lines in Fig. 6. When the machine is in operation, these rollers 52 are continuously driven in clockwise directions with respect to Fig. 7 by sprockets 56 fast on the rear ends of rollers 52, a link chain 57 running over said sprockets, a pair of bevel gears 58, one of which is mounted fast on the projected end of one

of said rollers 52, and other driving connections hereinafter to be described.

As an important feature of the invention, I provide a yielding stop device 59 for limiting lateral input feeding movements of the pallet 32 at a point where it becomes properly aligned with the mold cavity and is ready for elevation to the mold. This yielding stop device 59 comprises a pivoted arm 60 mounted fast on a pivot shaft 61 and having a pallet-engaging head 62. This yielding stop device 59 is free to rock pivotally from its full line intermediate position of Fig. 7 to its opposite extreme position shown by dotted lines in Fig. 7, and is yieldingly biased toward its intermediate full line position preferably by gravity acting through a depending weighted arm 63. Under input feeding movements of the pallet from left towards the right in respect to Fig. 7, the pallet will strike the head 62 of the stop device and move the same pivotally from its full line position to its right-hand dotted line position of Fig. 7, at which point the biasing pressure resulting from the action of gravity on the weighted arm 63 will overcome the frictional driving engagement of the rollers 52 on the pallet and stop the pallet. At this point it may be said that the inclination of the stop arm 60, shown in Fig. 7, is important in that it permits downward displacement to its left-hand dotted line position of Fig. 7 when the pallet is lowered onto the rollers from its operative position. The rock shaft 46 is journalled at its end in the frame 1.

Mounted above the mold cavity is a laterally spaced series of tampers, each comprising a cylindrical shank 64 and a foot 65 rigidly but detachably carried by the lower end of its cooperating shank 64. The tamper shanks 64 are vertically extended and are axially slidably mounted at their upper and lower ends respectively in bearings formed in cross members 66 and 67 respectively. Each tamper shank 64 carries a guide shoe 68, as shown best in Figs. 5 and 10.

The several tampers are gravity biased in a downward direction and are each raised to their uppermost positions shown in Fig. 5 by a different cooperating cam. The said tamper-actuating cams each comprise a cam arm 69 having a roller head 70 journalled on its free end for engagement with a cooperating cam shoe 68. These several cam arms 69 are mounted in spaced relation on a common rotary cam shaft 71 that is journalled at its outer ends in frame-supported bearings 72. The cam arms 69 may be secured to the cam shaft 71 in any suitable manner, but, as shown, are welded directly thereto. Each roller cam head 70 underlies the shoe 68 of a different tamper and the cam arms 69 are equally circumferentially spaced about the axis of cam shaft 71. The direction of rotation of the cam shaft and cams is counterclockwise with respect to Fig. 5, as indicated by arrows on Fig. 5, and each cam is circumferentially advanced with respect to the preceding cam with the order of advancement or progression from one end of the shaft toward the other end thereof. The cam shaft 71 is continuously driven from a motor 73 through driving connections comprising a belt pulley 74 on the motor shaft, a belt 75 running over the motor pulley 74, and a speed reduction pulley 76 on one end of a transversely extended frame-journalled shaft 77, a relatively small belt pulley 78 fast on the other end of shaft 77, a belt 79 running over pulley 78, and a larger pulley 80 fast on one end of the cam shaft 71.

As has been heretofore made apparent, the cam

shoe of each tamper is adapted to vertically reciprocate into and out of the orbit of a different one of the several cam rollers 70, and would, therefore, be subject to continuous reciprocation together with its respective tamper were it not for some device for locking the unit in an upper position where its cam shoe is out of the orbit of the cam roller. For the purpose of thus locking the several tampers independently in their upper inoperative positions, I provide locking device 81 for each tamper. Each locking device 81 comprises a pawl-acting latch finger 82 and a cooperating stop element 83; the latter serving as a ratchet tooth. The ratchet tooth-acting stop elements 83 are each in the nature of a split collar clamped around the intermediate portion of a different tamper shank 64. The several latch fingers 82 are each pivotally mounted at its lower end on a rock shaft 84. The rock shaft 84 is journaled adjacent its opposite ends in frame-supported bearings 85 (see Fig. 2). The latch fingers 82 are yieldingly connected to the rock shaft 84 for movements therewith by connections comprising short arms 86 fast on the rock shaft 84, threaded bolts 87 carried by and extending from the latch fingers 82 and working through the arms 86, and opposed compression springs 88 and 89. The opposed compression springs 88 and 89 are maintained under desired pressure by nuts on the outer ends of bolts 87. Movements of the several latch fingers 82 from their operative positions shown by full lines in Fig. 5 to their inoperative positions shown by dotted lines in Fig. 5 and back to their operative positions are accomplished by manual rocking of shaft 84 through the medium of a handle-equipped lever 90, see Fig. 8. The manual operating lever 90 is mounted fast on the rock shaft 84, and said rock shaft 84 and its several latch fingers 82 are spring biased toward operative positions by a coil tension spring 91 anchored at one end to the intermediate portion of lever 90 and at its other end to the frame 1; the latter point of connection of spring 91 being best shown at 92 in Fig. 2. Movements of the several latch fingers 82 in directions of their inoperative positions are limited by a transverse stop bar 93 suitably supported from the frame 1.

Contrary statements above notwithstanding, the ends of the tamper shoes 68 project just slightly into the orbits of their respective cam rollers 70 when the tampers are resting on the latch fingers 82. With the arrangement described, the spring 91 tends to move the free ends of latch fingers 82 against their respective tamper shanks 64 so that they drop under their respective cooperating stop elements 83 on their first upward movements upon release of handle-equipped lever 90 and lock their respective tampers against downward movement responsive to gravity. With the arrangement described, it will further be seen that the tampers, due to the projection of the shoes 68 into the orbits of rotation of respective cooperating cam rollers 70, will be lifted slightly off of their respective cooperating latch fingers 82 under each rotation of a cooperating cam roller 70. This slight reciprocation of each tamper for each rotation of its respective cam when the latch elements 82 are in operative positions is important in that it results in releasing the latch elements one at a time and momentarily responsive to yielding action of their respective springs 89 whenever the control lever 90 is manually re-traced to its latch unlocking position. Similarly, when the manual control lever 90 is released, the spring 91 places the several latches 81 under pres-

sure to move toward locked positions one by one as their respective cooperating stop elements 83 move upwardly past the free ends of fingers 82, and under which action the springs 88 yield to permit such upward passage of stop elements 83 past the upper ends of their cooperating fingers 82.

By reference particularly to Fig. 5, it will be seen that the shoe 68 of each of the several tampers works slidably over a guide rod 94 secured in frame members 66 and 67 and extending in parallel spaced relation to the tamper shanks 64.

The driving connections not yet completely described include three identical trip clutches indicated by A, B, and C respectively mounted on transverse shafts 95, 96, and 97 respectively. The shafts 95, 96, and 97 are journaled in frame-mounted bearings best shown in Figs. 2, 3, and 4.

The trip clutches A, B, and C are of a well-known conventional variety each comprising an internally corrugated drum 98 mounted loosely on its respective shaft 95, 96, or 97, a cooperating flange 99 fast on its respective shaft, and a pair of T-shaped levers 100 that are intermediately pivoted to the flange 99 at 101. One arm of each of the T-shaped levers 100 carries a drive roller 102 that is adapted to engage the corrugated inner surface of the drum 98 to establish driving engagement between the flange 99 and drum 98. The T-shaped levers 100 are connected by a pivoted link 103 and the outwardly projected arms 104 of levers 100 serve as trip fingers. By reference particularly to Fig. 11, it will be seen that the levers 100 are spring biased in directions to move their respective rollers 102 into driving engagement with the interior of drum 98 by a spring 105. The arms 104 of levers 100 project outwardly between flange 99 and drum 98 as shown best in Fig. 4. The peripheries of the flanges 99 of the trip clutches A, B, and C are formed with diametrically opposed notches 106 for reception of cooperating trip rollers 107. These notches 106 are so orientated that they will be in line each with a different trip finger 104 when the T-shaped levers 100 are in their operative positions wherein their drive rollers 102 are in operative driving engagement with the inner periphery of drum 98. The trip fingers 104 are essentially moved to their inoperative positions shown in Fig. 11 when the trip rollers 107 drop into either of the opposed notches 106. The trip rollers 107 of trip clutches A, B, and C are journaled in the bifurcated end portions of trip arms 108, 109, and 110 respectively. These trip arms 108, 109, and 110 are respectively mounted fast on frame-journalled rock shafts 111, 112, and 113.

The trip arm 108 of trip clutch A is manually controlled through a lever 114 fast on shaft 111, a rigid link or rod 115 extending from the free end of lever 114 to the intermediate portion of a handle-equipped operating lever 116 located at the front end of the machine and which is pivotally connected at 117 to the frame 1. The trip linkage of trip clutch A, just described, is biased toward trip clutch release position by a coil tension spring 118 anchored at one end to rod 115 and its other end to the frame 1.

The trip clutch B is manually operated through a linkage comprising a lever 119 fast on shaft 112, a rigid link or rod 120 pivotally connected to the free end portion of said lever and extending to and pivotally connected to the intermediate portion of a handle-equipped operating lever 121. The lever 121 is located at the front of the ma-

chine and is pivoted at its lower end to the frame 1 at 122. The operating linkage of trip clutch B is spring biased to clutch release position by a coil tension spring 123 anchored at one end to lever 119 and at its other end to frame 1.

Trip clutch C is automatically operated responsive to rotation of shaft 96 under control of trip clutch B through the following noted mechanism, to wit: A diametrically opposed pair of rollers 124 are journaled to shaft 96 through the medium of radially projecting arms 125 fast on said shaft 96. These diametrically opposed rollers 124 each engage and impart rocking movement to a lever 126 and rock shaft 113 on which said lever 126 is secured once for each 180° of rotation of shaft 96. The lever 126 is spring biased toward a clutch release position by a coil tension spring 127 extending between said arm and a cross member of the frame 1.

With the clutches A, B, and C and the control mechanism therefor, the trip clutches A and B will each operate its respective shaft 95 or 96 180° each time a cooperating control lever 116 or 121 is momentarily actuated to release its cooperating trip roller 107 from a cooperating notch 106, and for each 180° of rotation of shaft 96 trip clutch C will be rendered operative to drive its shaft 97 180°.

The pitman arms 28, for imparting reciprocating movements to the troweler or transfer device 22, are driven from counterweighted cranks 128 on opposite ends of shaft 95. The mold opening and closing pitman arm 15 is operated by a short crank 129 (see Figs. 2 and 4), so that the mold will open responsive to one 180° of rotation of shaft 96 and will close on the succeeding 180° of movement of shaft 96.

The pitman 51 of the elevator mechanism is connected at its outer end to a crank arm 130 fast on shaft 97 controlled by trip clutch C. With the pitman arm 51 thus connected to shaft 97, the pallet elevating mechanism, including I beams 33, will be lifted to its upper position responsive to one 180° of movement of the shaft 97, and will be lowered responsive to the succeeding 180° of movement of shaft 97. It will here be noted that the weight of the I beams 33 of the elevator mechanism is partially counterbalanced by means of a counterbalancing spring 131 that is anchored at one end to the frame and at its other end to the arm 132 fast on shaft 46.

The pair of bevel gears 58 for driving the horizontal conveyor rollers 52 are mounted one fast on one of the rollers 52 and the other fast on a transverse drive shaft 133 that is mounted in bearings 134 on the frame 1. Short drive shaft 133 is continuously driven from the continuously operating cam shaft 71 through driving connections comprising a double V groove pulley 135 on one end of the cam shaft 71, a pair of V belts 136, another double V groove pulley 137 that is mounted fast on one end of a shaft 138 that is mounted in bearings 139 on the frame 1, a chain sprocket 140 on said shaft 138, and a chain 141 running over said sprocket 140 and a sprocket 142 on the shaft 133.

The floating or loosely mounted drum 98 of trip clutch A is driven from continuously operating shaft 138 through connections comprising a sprocket 143 fast on said shaft 138 and a chain 144 running over said sprocket 143 and running over a similar sprocket 145 that is fast on the hub 98 of said loosely mounted or floating trip clutch element 98 of clutch A. The loosely mounted or floating drum element 98 of clutch

B is similarly continuously driven from shaft 138 through driving connections comprising a sprocket 146 fast on shaft 138 and a chain 147 running over said sprocket 146 and a similar sprocket 148 fast on the hub of element 98 of clutch B. The loosely mounted or floating drum element 98 of trip clutch C is continuously driven in common with the element 98 of trip clutch B through driving connections comprising a sprocket 149 also fast on the hub of element 98 of clutch B and a chain 150 running over said sprocket 149 and a similar sprocket 151 on the hub of element 98 of trip clutch C.

Operation

To initiate the operation or a series of operations, the electric motor 73 will be started, whereby all of the before-mentioned continuously operating elements will be operative. With the elevator beams 33 retracted to their lower positions shown by dotted lines in Fig. 6, a pallet 32 will be placed upon the now continuously operating rollers 52 through the front of the machine. This pallet 32 will now be conveyed from left to right with respect to Fig. 7, or laterally of the machine, towards the stop device 59. As the pallet 32 is thus conveyed by rollers 52 from left toward the right with respect to Fig. 7, it will engage the head 62 of yielding stop device 59 and will move the same from its intermediate full line position of Fig. 7 to its right-hand dotted line position of Fig. 7, at which point the weighted arm 63 of yielding stop device 59 will set up sufficient resistance to stop the pallet 32 in spite of continued rotation of the conveyor rollers 52. The pallet 32 will now be properly positioned below the cavity of mold 2. The next operation is to elevate the pallet 32 to its operative position under the mold cavity, and this is accomplished as follows: The operator will momentarily pull lever 121 and then release the same, thereby disengaging trip roller 107 of clutch B from a cooperating notch 106. This releasing of roller 107 of clutch B from its cooperating notch 106 will result in a one-half turn or 180° of rotation of shaft 96, which will cause pitman 15 to move from one extreme position to the other and close the mold 2. Another result of the above-mentioned one-half turn of shaft 96 is as follows: A roller 124 carried by shaft 96 will engage and rock arm 126 and rock shaft 113, which will cause tripping of clutch C. When clutch C is tripped, shaft 97 will partake of 180° of rotary movement, thereby moving the pitman 51 from one extreme position to its opposite extreme position and causing the elevator mechanism to lift the beams 33 thereof and the pallet 32 to their upper positions wherein the pallet contacts the bottom of the mold 2 and closes the bottom of the mold cavity. At this point, it should be understood that the troweler or transfer device 22 will be positioned below the open end of the delivery conduit 25 and will have been filled with a work batch of concrete; the bottom of troweler 22 being now closed by plate or shelf 20. The operator will now momentarily retract lever 116 against the action of spring 118 to thereby trip clutch A, which will result in a 180° rotation of shaft 95 and moving of pitman 28 from one extreme position to the other. This movement of pitman 28 will cause the transfer device or troweler 22 to be moved from its receiving position under the spout or conduit 25 to its delivery position above the mold (see Fig. 5). When the transfer device or troweler 22 is thus removed from its receiving to its delivery position,

the bottom of the spout or conduit 25 will be automatically closed off by the valving plate 27 and part of the work batch *y* will drop into the cavity of mold 2 and onto the pallet 32.

We are now ready for the tamping operation, which is initiated by manually pulling lever 90 against the action of tension spring 91 and sufficiently to compress the several compression springs 88 of the several locking devices 81. Since the bolts 87 work loosely through the short arms 86 of their respective locking devices, the said compression of the springs 88 will tend to pull said bolts and the latch fingers 82 outwardly to their inoperative positions shown by dotted lines in Fig. 5. Under this yielding outward tension, the several latch fingers 82 will be released from their respective cooperating stop elements 83 and permitted to so move to their inoperative positions one by one as their respective cooperating cam rollers 70 engage and slightly lift their respective cooperating tamper shoes 68. After the cam shaft 71 has made one complete revolution, all of the tampers will be in operation, vertically reciprocating from their upper positions shown in Fig. 5 to their lower dotted line positions shown in Fig. 5. It will be understood that the operator will hold the tamper control lever 90 in its outer tamper-operative position for the duration of the tamping operation, upon completion of which he will release the lever 90 and permit the several locking devices 81 to return to their tamper latching or locking positions under the yielding action of spring 91. When the lever 90 is thus released, the latch fingers 82 will automatically come into operative locking engagement with their respective stop elements 83 one at a time as their respective tampers are raised to their uppermost positions. As the tamper feet 65 come into intermittent engagement with the upper portion of the work batch *y* of concrete or other cementitious material within the troweler or transfer device 22, the said work batch, including that portion thereof within the mold cavity, will be compacted to a maximum density. Usually the duration of the tamping period need be but a few seconds, but will vary somewhat with the type and consistency of the material employed.

With the tamping operation thus completed and the tampers all returned to their upper inoperative full line positions of Fig. 5, the next step in the operation will be to trowel off the work batch even with the top of the mold cavity, and this is accomplished by returning the troweler or transfer device 22 from its delivery position of Fig. 5 to its receiving position of Fig. 6. As previously indicated, this last noted operation is accomplished mechanically under manual control as follows, to wit: The operator will momentarily retract lever 116 against the action of spring 118, thereby operating link 115, crank arm 114, trip lever 108, and trip roller 107 of trip clutch A, which will trip clutch A and permit it to drive the shaft 95 180° to operate the pitman arms 28 and return the troweler or transfer device 22 from its delivery position of Fig. 5 back to its receiving position of Fig. 6. The transfer device or troweler 22 will now be refilled, by gravity action, with cementitious material from the source through delivery conduit or chute 25.

Now we come to the final tamping or surface finishing operation, which is accomplished as follows: With the parts positioned as shown by full lines in Fig. 5, the tamping or finishing plate 29, which all during the preceding operations has been in its vertical inoperative position in

Fig. 5, will now be moved pivotally from its said vertical inoperative position of Fig. 5 to its horizontal operative position of Fig. 6, after which the tampers will again be operated for a short period of time in the manner and by mechanism previously described. During this secondary tamping or finishing operation, the bottom surface of the tamping or finishing plate 29, which in the present instance is shown as being corrugated, will contact the upper surface of the material *y* in the mold cavity and will be vibrated thereon by intermittent engagement with its upper surface of the shoes 65 of the several tampers. This secondary tamping or finishing operation lasts usually but a few seconds, and upon completion thereof we have a finished block or stave in the mold cavity, and the plate 29 may now be moved back to its vertical inoperative position.

The next operation is to open the mold 2 to release the finished stave or block, remove the said finished block or stave from the mold cavity, and convey the same to a suitable delivery point. This is the final operation and is accomplished as follows: To initiate this composite operation or series of related operations, the operator momentarily retracts operating lever 121 to thereby trip clutch B to drive shaft 96 180° of rotary movement and open the mold through action of pitman arm 15 in the manner heretofore described. Now, as previously explained, this 180° mold-opening movement of shaft 96 under control of trip clutch B automatically trips elevator control mechanism clutch C through connections comprising an arm 125, a roller 124, rock arm 126, rock shaft 113, and the trip arm 110 and trip roller 107 of clutch C. As a result of this automatic tripping of clutch C, the shaft 97 is given 180° of rotation, which will lower the elevator beams 33, the pallet 32, and the finished block or stave supported thereon to their lower positions shown by dotted lines in Figs. 6 and 7. During the lowering movement of the elevator beams 33 and pallet, the pallet contacts the head 62 of the yieldingly biased stop arm 60 and moves the same from its intermediate full line position of Fig. 7 to its left-hand position of Fig. 7, where it is rendered inoperative and will permit free lateral movement of the pallet under the action of the continuously driven conveyor rollers 52. Under frictional driving engagement of these conveyor rollers 52 with the bottom of the pallet, the pallet will move to the right in respect to Fig. 7 and will be delivered to a suitable delivery point or conveyor mechanism. The pallet, complete with its molded product, will usually be stacked with others for drying and hardening. Of course, when the pallet has been conveyed past the head 62 of stop arm 60, the said stop arm 60 will return under the yielding action of gravity to its intermediate full line operative position of Fig. 7. The machine will now be ready for a succeeding block-molding operation of the kind described above.

What I claim is:

1. In a machine of the kind described, a mold having a molding cavity opening through its bottom, a pallet adapted to close the bottom of the mold cavity, a horizontal conveyor located below the plane of the bottom of the mold and having its intermediate portion directly beneath the mold, said horizontal conveyor comprising laterally spaced conveyor rollers and extending from a receiving point laterally offset from the mold in one direction to a delivery point laterally offset from the mold in another direction, an ele-

vator platform element located below the mold and mounted for approximately vertical movements between adjacent cooperating rollers of the horizontal conveyor, whereby to raise a pallet off of the intermediate portion of the conveyor into operative engagement with the bottom of the mold and return the same to the intermediate portion of the conveyor for continued conveyance by the latter, said horizontal conveyor rollers being continuously driven in like directions, a stop arm pivotally mounted below the plane of the upper surfaces of the conveyor rollers on an axis substantially parallel to the axes of the rollers and having a free head end swingable into and out of the path of travel of a pallet moving on the horizontal conveyor rollers, and means yieldingly biasing said stop arm to an intermediate position wherein it is inclined in a direction opposing the direction of horizontal feed and wherein its head is in the path of travel of a pallet on the horizontal conveyor, the yielding biasing force on the stop arm being sufficient to stop a pallet after a pre-determined movement of the stop arm in the direction of horizontal feed, whereby the stop arm will be returned to its said inclined intermediate position upon elevation of the pallet and will be deflected to an inoperative position below the pallet upon lowering of the pallet to the conveyor rollers, thereby permitting continued unidirectional horizontal feeding movements of the pallet upon return to the horizontal conveyor rollers.

2. In a machine of the kind described, a mold having a molding cavity opening through its bottom, a pallet adapted to close the bottom of the mold cavity, a horizontal conveyor located below the plane of the bottom of the mold and having its intermediate portion directly beneath the mold, said horizontal conveyor comprising laterally spaced conveyor rollers and extending from a receiving point laterally offset from the mold in one direction to a delivery point laterally offset from the mold in another direction, an elevator platform element located below the mold and mounted for approximately vertical movements between adjacent cooperating rollers of the horizontal conveyor, whereby to raise a pallet off of the intermediate portion of the conveyor into operative engagement with the bottom of the mold and return the same to the intermediate portion of the conveyor for continued conveyance by the latter, said horizontal conveyor rollers being continuously driven in like directions, a stop arm pivotally mounted below the plane of the upper surfaces of the conveyor rollers on an axis substantially parallel to the axes of the rollers and having a free head end swingable into and out of the path of travel of a pallet moving on the horizontal conveyor rollers, and means yieldingly biasing said stop arm to an intermediate position wherein it is inclined in a direction opposing the direction of horizontal feed and wherein its head is in the path of travel of a pallet on the horizontal conveyor, the yielding biasing force on the stop arm being sufficient to stop a pallet after a pre-determined movement of the stop arm in the direction of horizontal feed, whereby the stop arm will be returned to its said inclined intermediate position upon elevation of the pallet and will be deflected to an inoperative position below the pallet upon lowering of the pallet to the conveyor rollers, thereby permitting continued unidirectional horizontal feeding movements of the pallet upon return to the horizontal conveyor rollers.

ing movements of the pallet upon return to the horizontal conveyor rollers, said yielding biasing means for the pivoted stop arm comprising a weighted pendulum-acting arm rigid with the pivoted stop arm and depending substantially vertically from the axis of the stop arm when the stop arm is in its aforesaid inclined intermediate position.

3. In a machine of the kind described, a mold having a molding cavity opening through its bottom, a pallet adapted to close the bottom of the mold cavity, a horizontal conveyor located below the plane of the bottom of the mold and having its intermediate portion directly beneath the mold, said horizontal conveyor comprising laterally spaced conveyor rollers and extending from a receiving point laterally offset from the mold in one direction to a delivery point laterally offset from the mold in another direction, an elevator platform located below the mold, elevator mechanism supporting said platform and adapted to move the same vertically from inoperative position below the plane of the upper surfaces of the conveyor rollers upwardly between adjacent conveyor rollers and into operative position wherein it will support a pallet against the bottom of the mold, said horizontal conveyor rollers being continuously driven in like directions, a stop arm pivotally mounted below the plane of the upper surfaces of the conveyor rollers on an axis substantially parallel to the axes of the rollers and having a free head end swingable into and out of the path of travel of a pallet moving on the horizontal conveyor rollers, and means yieldingly biasing said stop arm to an intermediate position wherein it is inclined in a direction opposing the direction of horizontal feed and wherein its head is in the path of travel of a pallet on the horizontal conveyor, the yielding biasing force on the stop arm being sufficient to stop a pallet after a predetermined movement of the stop arm in the direction of horizontal feed, whereby the stop arm will be returned to its said inclined intermediate position upon elevation of the pallet and will be deflected to an inoperative position below the pallet upon lowering of the pallet to the conveyor rollers, thereby permitting continued unidirectional horizontal feeding movements of the pallet upon return to the horizontal conveyor rollers.

NEWELL B. HANSON.
